TOY SPINNING TOP

Peter Balleis, 55 Hermann-Lons-Strasse, Zirndorf,
near Nuremberg, Germany

Filed Dec. 5, 1966, Ser. No. 4,916

Claims priority, application Germany Oct. 28, 1966

Term of patent 7 years

(Cl. D34—15)

FIG. 1

FIG. 2

FIG. 1 is a side elevational view of a toy spinning top showing my new design; and

FIG. 2 is a top perspective view thereof.

The characteristic feature of my design resides in the particular lunar surface and space ship representations in combination with the toy spinning top, all as shown.

I claim:

The ornamental design for a toy spinning top, as shown and described.
